UNITED STATES PATENT OFFICE

WILLIAM F. PUNTE, OF SYRACUSE, NEW YORK, ASSIGNOR TO CONTINENTAL CAN COMPANY, INC., OF NEW YORK, N. Y., A CORPORATION OF NEW YORK

METHOD OF SEALING METAL CONTAINER

Application filed June 29, 1931. Serial No. 547,734.

The invention relates to new and useful improvements in metal containers, and more particularly to the method of sealing metal containers. It has been a common expedient 5 in the art to provide the body portion of a metal container with a horizontally projecting flange and the cover portion for the container with a similar horizontally projecting flange, which overlies the flange on the body 10 portion, to place a sealing material between the flanges and secure the flanges by a sealing strip which embraces both flanges. It is difficult to obtain a proper seal in a container of this type and also to secure the sealing 15 band to the projecting flanges so that it will hold the flanges in tight sealing contact with the sealing material, and at the same time permit easy removal of the sealing strip.

An object of the present invention is to 20 provide a construction of container and a method of sealing the same whereby a tight seal is obtained between projecting flanges which are enclosed within the sealing strip.

In the drawing—

25 Figure 1 is a view partly in side elevation and partly in vertical section, showing a container embodying the improvements and sealed by the improved method;

Fig. 2 is a vertical sectional view showing 30 in full lines the cover in its normal condition and before it is applied to the container body, and in broken lines, the cover as applied to the container body but before the sealing strip has been attached for sealing the container;

35 Fig. 3 is a view showing in broken lines one way of applying a sealing strip, and in full lines the position of the sealing strip when the container is sealed, and

40 Fig. 4 is a view showing the method of attaching a slightly different form of sealing strip, and the sealing of the container.

The container includes a body portion indicated at 1 in the drawing. The body portion has one end thereof closed by a container 45 end 2 which is secured to the body portion by

a double seam 3. The body portion at the other end thereof is provided with a flange 4. The container body is closed by a cover or end 5 having a central depressed portion 6 which fits within the body portion. Said cover also 50 has a projecting flange 7 which is curved so as to provide a channel 8 on its under face. The cover is inverted and the channel filled with a sealing material 9. After the sealing material is set, it is retained within the channel 55 and the cover may be inverted and applied to the container. The flange 4 has a horizontal face extending substantially from the point 4^a to the point 4^b at the extreme outer edge of the flange. The cover flange 60 is curved from the point 7^a to the point 7^b which forms the channel 8 for the sealing material. The flange of the cover or end 5 when curved or in its normal condition, is of less maximum diameter than the flange 4 of 65 the body, and therefore, when the cover is inserted in the body, the extreme outer edge 7^b of the cover or end will engage the flange 4 substantially at the point 4^c. After the cover has been placed on the container body, 70 a sealing strip 10 is applied to the cover. The sealing strip 10, as shown in Fig. 3, has the side portions thereof arranged substantially at right angles to each other. Pressure is applied to the upper portion of the sealing 75 strip so as to force the flange 7 of the cover into a horizontal position. This will squeeze the sealing material outward and inward, thus making a very tight seal between the two flanges. The under side portion 11 of the sealing strip is then forced underneath the lower flange so as to tightly grip and hold the flanges in parallel relation, after the pressure 80 has been relieved from the upper face of the sealing strip. The sealing strip is gripped by the tendency of the curved flange to spring 85 back to its curved condition, and this will hold the sealing strip firmly connected to the parallel projecting flanges. The sealing strip 90 also will hold the flange 7 in its horizontal

position, pressing against the sealing material, and thus forming a very tight seal.

In Fig. 4 of the drawing, a slightly different method of attaching a sealing strip to the flanges of the container is shown. In this form of the invention, the sealing strip is substantially V-shape in cross section, and is rolled into hook form, and then placed around the flanges of the can body and the can end or cover. The can body with the cover placed thereon with the sealing strip in place, is positioned in the lower die ring 13. The upper die ring 14 is lowered, and the portion 14* thereof is brought into contact with the sealing strip. The relative movement of the die rings will force the upper and lower portions of the sealing strip into contact with the flanges, and will straighten the curved flange on the cover, bringing said flanges and the sealing strip into the position shown in full lines in Fig. 3. The same tight grip of the sealing strip on the flanges is obtained, and the same tight sealing of the container produced.

It is obvious that the sealing strip may be otherwise applied to the container. The essential feature, however, of the method consists in the curving of the flange on the end to form a channel or pocket for the sealing material, and the forming of the flange on the body substantially horizontal, so that it will cooperate with the sealing strip, when applied, to straighten out the flange on the cover or can end, and thus press the sealing material into intimate contact with the parts, producing a closure which is not only a tightly sealed closure, but one which may be readily opened by a horizontal force applied in an outward direction on the sealing strip.

Having thus described the invention, what I claim as new and desire to secure by Letters Patent, is—

1. The method of forming an hermetically sealed metal container consisting in providing the container body with an outwardly extending substantially horizontal flange, and a cover for the container with a peripheral flange adapted to overlie the flange on the body and normally curved upwardly between the inner and outer edges of the flange to form a channel on the under face thereof, placing a plastic sealing material in said channel and the cover on the container body, and sealing the container by applying a sealing strip thereto which embraces the flanges and forces the curved flange on the cover into parallelism with the horizontal flange on the container body.

2. The method of forming an hermetically sealed metal container consisting in providing the container body with an outwardly extending substantially horizontal flange, and a cover for the container with a peripheral flange normally curved upwardly between the inner and outer edges of the flange, to form a channel on the under face thereof, said flange

on the cover, when curved, being of less diameter than the flange on the container body, so as to rest thereon when the cover is applied to the container body, placing a plastic sealing material in the channel and the cover on the container body and sealing the container by applying a sealing strip thereto which embraces the flanges and forces the curved flange on the cover into parallelism with the horizontal flange on the container body.

In testimony whereof, I affix my signature.

WILLIAM F. PUNTE.
